UNITED STATES PATENT OFFICE.

CLARENCE E. WYRICK, OF PEABODY, KANSAS.

LADDER.

1,360,854.

Specification of Letters Patent. Patented Nov. 30, 1920.

Application filed May 17, 1920. Serial No. 382,161.

To all whom it may concern:

Be it known that I, CLARENCE E. WYRICK, a citizen of the United States, residing at Peabody, in the county of Marion and State of Kansas, have invented new and useful Improvements in Ladders, of which the following is a specification.

This invention relates to improvements in ladders and has for an object the provision 10 of a step ladder of sectional formation which is capable of being folded into compact form for transportation or storage.

To this end the invention contemplates the provision of a novel form of hinge for connecting the ladder sections together, the construction being such as to lock the hinge against folding movement until the sections are moved longitudinally with respect to one another and to space the sections apart 20 after the hinge has been folded to permit of the ladder sections being folded over one another.

Other objects and advantages of the invention will appear as the following description is read in connection with the accompanying drawings.

In the drawings:—

Figure 1 is a view in side elevation of a step ladder embodying the present invention.

Fig. 2 is a front elevation.

Fig. 3 is a central vertical section.

Fig. 4 is a side elevation of the ladder folded.

Fig. 5 is an end view of the same.

Fig. 6 is an enlarged fragmentary elevation of the hinge which connects the ladder sections, showing the position of the hinge when the ladder is set up.

Fig. 7 is a similar view showing the position of the hinge when the ladder is folded.

Referring specifically to the drawings wherein like characters of reference denote corresponding parts, the ladder is made up 45 of two sectional members, the one which is indicated at 10 will be hereinafter referred to as the rung member, while the other is indicated at 11 and will be herein-after referred to as the brace member. These 50 members 10 and 11 are hingedly connected at their upper ends and for this purpose the rung member 10 is provided with spaced arms 12, one end of which is rigidly secured to the rung member while their opposite

55 ends are pivotally connected to the brace member as indicated at 13. The rung mem-

ber is preferably formed of angle iron and includes sectional side bars 14 which are connected by rungs 15.

Each section of the rung member is hingedly connected to the adjacent end of the adjoined section by means of a hinge 16. This hinge comprises a plate 17 which is provided with oppositely extending inclined slots 18, the latter being adapted to receive 60 studs 19 carried by the side bars of the rung member sections. The slots 18 of the plates 17 are so disposed that when the hinge is in the position shown in Fig. 6, one side edge of the plate 17 abuts one of the flanges of 70 the angle iron of which the side bars 14 are formed, so that in order to operate the hinge it is necessary to move the sections longitudinally with respect to one another, whereupon the members may be moved pivotally 75 and spaced apart as indicated in Fig. 7.

The brace member 11 is also formed of angle iron and includes sectional side bars 20 which are connected by braces 21 and 22 to lend rigidity to the brace member. The 80 sections of the brace members are also pivotally connected together by hinges 23, which are similar in construction to the hinges 16 previously described, so that when the adjacent ends of the side bars 20 abut, the sections will be held against relative pivotal movement.

When the ladder is set up the rung member and brace member may be connected by hooks 24 to hold the said members in position. When in folded position, hooks 25 serve to hold the sections properly arranged. If desired, one of the sections may have connected to it a handle 26 for conveniently carrying the ladder.

By reason of the formation of the hinges 16 and 23, the ladder may be folded with the sections folded over one another to provide a compact arrangement illustrated in Figs. 4 and 5.

The invention is susceptible of various changes in its form, proportions and minor details of construction and the right is herein reserved to make such changes as properly fall within the scope of the appended 105 claims.

Having described the invention what is claimed is:—

1. A step ladder comprising a sectional rung member and a sectional brace member, 110 means for pivotally securing the upper ends of said members together in spaced relation

and means including sliding pivotal connections, whereby the sections of the members will be held against pivotal movement when their ends are arranged in contacting relation.

2. A step ladder comprising a sectional rung member and a sectional brace member, means for pivotally securing the upper ends of said members together in spaced relation 10 and hinges for pivotally connecting the sections of the rung and brace members, said hinges each comprising a plate having oppositely inclined slots and studs carried by the

adjacent ends of the sections and engageable in said slots.

3. A hinge for connecting the abutting ends of two angle iron sections comprising a plate having oppositely inclined slots and studs carried by the adjacent ends of the sections and engageable in said slots, the latter being so arranged as to force one edge of the plate against one flange of the angle iron when the ends of the sections are in abutting relation.

In testimony whereof I affix my signature. 25

CLARENCE E. WYRICK.
